J. HAY.

BED WARMER.

APPLICATION FILED NOV. 7, 1910.

1,005,030.

Patented Oct. 3, 1911.

UNITED STATES PATENT OFFICE.

JOHN HAY, OF CARMEL, CALIFORNIA.

BED-WARMER.

1,005,030.

Specification of Letters Patent.

Patented Oct. 3, 1911.

Application filed November 7, 1910. Serial No. 591,140.

To all whom it may concern:

Be it known that I, JOHN HAY, a subject of the King of Great Britain, residing at Carmel, in the county of Monterey and 5 State of California, have invented certain new and useful Improvements in Bed-Warmers, of which the following is a specification.

This invention relates to bed warmers 10 and is designed to construct a bed warmer which will conduct the heat from a lamp or other heat generating apparatus to the bed, said heat generating apparatus being located away from the bed. It also contemplates 15 the construction of a warmer which will be provided with a means whereby the lamp which generates the heat may be extinguished.

With the above and other objects in view, 20 this invention consists in the construction, combination and arrangement of parts all as hereinafter more fully described, claimed and illustrated in the accompanying drawings, wherein:

25 Figure 1 is a side elevation of a bed warmer constructed in accordance with the present invention, parts thereof being broken away; Fig. 2 is a bottom plan view of the heat accumulator and conductor; Fig. 3 is an inside elevation of the cap located at the top of the fume and smoke conducting chimney; Fig. 4 is a fragmentary elevation of a portion of the outer casing of the heat accumulator, illustrating the catch securing 35 said heat accumulator to the lamp; Fig. 5 is a perspective view of the lamp illustrating the lug adapted to coöperate with the catch illustrated in Fig. 4; Fig. 6 is a fragmentary view of the heat accumulator illustrating 40 the intermediate catches; Fig. 7 is a top plan view of the lamp.

The bed warmer forming the subject-matter of the present invention comprises a spirit lamp having a series of off-set lugs 45 located on the upper surface thereof, one of said lugs being provided with recesses. A conical heat accumulator is provided with inwardly projecting extensions to engage said lugs, one of said catches being bent 50 upon itself forming a spring handle located on the exterior of the outer portion of said accumulator, said spring handle being adapted to engage the recess formed in one of said lugs carried by the spirit lamp. The 55 accumulator is formed in two sections, the space between said sections forming a heat

conductor which carries the heat to a flexible distributor adapted to be placed in or on a bed. The inner section of the distributor forms a conductor for the heat and fumes, 60 and is provided at its upper extremity with a cap to which a tube extends through the instrumentality of which the flame of the spirit lamp may be extinguished.

Referring to the drawings, 10 indicates a 65 spirit lamp having the burner 11 centrally located thereon. A series of upwardly offset lugs 12 and 12' surround the burner 11, the lug 12' being provided with a depression or recess 13.

A conical outer casing 14 is carried by the 70 lugs 12 and 12' and is provided with a series of downwardly and inwardly extending catches 15 and 15' at its lower edge, the catch 15' being bent upon itself and projected exteriorly under the lower edge of the casing 14, forming a handle and spring catch member 16. It will clearly be seen from the foregoing that the catches 15 co-operate with the lugs 12 upon a slight rotation of the casing 14, while the catch 15' co- 75 operates with the lug 12', the locking member 16 of the catch 15' engaging a recess 13 of the lug 12', thereby rigidly securing the conical casing 14 to the spirit lamp 10.

The conical outer casing 14 is provided 80 with a right angular tubular casing 17 at its upper extremity to which is connected a flexible heat distributor 18 as hereinafter more fully described. The opening 19 90 pierces the upper side of the tubular extension 17 and provides a means whereby the chimney may extend to and beyond said conical outer casing 14.

A conical chimney 20 is carried within the 95 casing 14 and is provided at its upper extremity with a tubular member 21 which extends through the opening 19 of the casing 14. It will be understood from this construction that the fumes, gases and the 100 like from the burner 11 do not enter into the heat distributor 18 but pass out through the tubular member 21. A cap or collar 22 is carried by the upper extremity of the tubular member 21 and has secured thereto a 105 tube 23, said tube extending into a portion of said collar or cap 22. By this construction it will readily be understood that by passing a current of air through the tube 23, the flame of the burner 11 will be extin- 110 guished.

The flexible heat distributor 18 which is

adapted to be retained in or on the bed is detachably secured to the tubular extension 17 of the outer casing 14 and contains the coil spring 24 which supplies the flexibility to the distributor. At the outer extremity of the heat distributor is a collar 25 to which is secured the cord or flexible member 26, which provides a means of retaining said distributor in various positions, as desired.

10 Having thus described the invention, what is claimed as new is:

1. In combination, a heat generator, a plurality of upwardly offset lugs mounted thereon, one of said lugs being provided with a recess in its outer edge, a casing having downwardly projecting extensions adapted to engage said lugs, said casings being spaced from said heat generator by said extensions, one of said extensions being bent 15 upon itself to form a spring member adapted to engage in said recess, and a lamp chimney mounted within said casing and retained in spaced relation thereto, as set forth.

2. In combination, a heat generator, a plurality of upwardly offset lugs mounted thereon, one of said lugs being provided with a recess in its outer edge, a casing having integral and inwardly projecting extensions thereon adapted to engage said lugs, said casing being spaced from said heat generator by said extensions, one of said lugs being extended to form a spring catch and a handle, said catch being adapted to engage in said recess, a horizontally disposed heat conducting member formed on said casing 25 said member being provided with an opening in its side, and a chimney mounted within said casing and projecting through said opening for the purposes set forth.

30 In testimony whereof I affix my signature 40 in presence of two witnesses.

JOHN HAY.
